(57) CLAIM

The ornamental design for a lace fabric, as shown and described.

DESCRIPTION

FIG. 1 is a front view of a lace fabric in accordance with the present invention.

FIG. 2 is a reference view of FIG. 1 with broken lines shown therein to indicate the area of detail view, FIG. 4.

FIG. 3 is a back side of FIG. 1; and,

FIG. 4 is an enlarged detail view of area 4 circumscribed by broken line in FIG. 2.

1 Claim, 4 Drawing SheetsFIG. 1

FIG. 4
